CLAIM

The ornamental design for a handle grip for vehicle, as
shown and described.

DESCRIPTION

FIG. 1 is a front elevational view of a handle grip for
vehicle showing my new design;

FIG. 2 is a top plan view thereof;

FIG. 3 is a left side elevational view thereof;

FIG. 4 is a right side elevational view thereof; and

FIG. 5 is a perspective view thereof.

The rear and bottom of the handle grip are substantially
mirror images of the front and top thereof shown in
FIGS. 1 and 2 respectively.
